PAIR OF GOGGLES

Helmut G. Tietje, Cresskill, N. J., assignor to
 Columbia Protekosit Company, Inc., a corporation of Delaware

Application November 22, 1952, Serial No. 22,407

Term of patent 3½ years

(Cl. D57—1)

To all whom it may concern:

Be it known that I, Helmut G. Tietje, a citizen of the United States of America and residing in the city of Cresskill, county of Bergen, and State of New Jersey, have invented a new, original, and ornamental Design for a Pair of Goggles, of which the following is a specification, reference being had to the accompanying drawings, forming a part thereof.

In the drawings:

Fig. 1 is a front elevational view of a pair of goggles, showing my new design; and

Fig. 2 is a top plan view thereof.

The characteristic features of my design reside in the configuration of the frame and the ornamentation thereon.

I claim:

The ornamental design for a pair of goggles, as shown and described.

HELMUT G. TIETJE.
